Filed Oct. 23, 1968, Ser. No. 14,122

Term of patent 7½ years

Int. Cl. D8—04

U.S. Cl. D8—274

FIG. 1 is a front view of a conduit locknut showing my new design;

FIG. 2 is a rear view of the nut shown in FIG. 1;

FIG. 3 is a left side view of the nut as shown in FIGS. 1 and 2;

FIG. 4 is a right elevational view thereof.

The characteristic feature of my design resides in the recessed lettered areas on the locknut face, as shown.

I claim:

The ornamental design for a conduit locknut, as shown and described.
